ATTORNEY

UNITED STATES PATENT OFFICE.

JOHN S. PIHLSTROM, OF MOBILE, ALABAMA.

REFRIGERATOR.

Application filed July 12, 1922. Serial No. 574,357.

To all whom it may concern:

Be it known that I, JOHN S. PIHLSTROM, a citizen of the United States, residing at Mobile, in the county of Mobile and State 5 of Alabama, have invented new and useful Improvements in Refrigerators, of which the following is a specification.

The object of this invention is to provide a device for storing food and keeping it 10 cool, without the use of ice, the device being of the general type known as a safe.

A further object is to effect the result desired by the use of a casing provided with inner walls of textile material and 15 particular means for keeping these walls moist, so that the air circulating through the outer perforated walls will constantly evaporate the water absorbed and conducted by the textile material.

20 A still further object is to provide a casing adapted to contain suitable shelving and having a water tank located in the upper portion, a trough located near the bottom, and inner walls, or curtains, extending 25 from the tank to the trough, and designed to be moistened by the water from the tank, the evaporation cooling the articles within the casing, or safe, and the trough retaining a sufficient quantity of water to protect 30 the food from ants or the like.

With the foregoing and other objects in view, the invention consists in the novel construction and arrangement of elements described and claimed, it being understood 35 that modifications may be made within the scope of the claims without departing from the spirit of the invention.

In the drawings, Figure 1 is a view of the 40 device in front elevation; Figure 2 is a side elevation; Figure 3 is a rear elevation; Figure 4 is a vertical section; Figure 5 is a horizontal section on the line 5—5 of Figure 1; Figure 6 is a perspective view of the upper tank, from which the textile 45 walls or curtains receive moisture.

The casing includes an upper portion 10, a lower portion 11, and structural corner elements, such as 12. The shelves 13 are carried by the transverse elements 14, and 50 it is the intention that there shall be a space between the series of shelves and the inner and outer walls of the complete device.

55 The doors 15 and 16 may be of usual construction, and wire netting, or other

equivalent material, is stretched over the openings of the doors, and about the other three sides of the safe.

Inner walls, or curtains 20, of textile material, extend from the top to the bottom and are located on at least three sides of the device. The curtains are intended to be free of the shelving and the outer walls of netting.

An upper tank 22 located in the portion 10 of the casing, contains a sufficient quantity of water, and the sides are provided with outwardly extending flanges 23 acting to space the curtains from the walls of the tank. Suitable engaging or attaching devices 24 are carried by the elements of the tank and permit the curtains to be suitably secured, these upper portions being immersed in the water.

The base on which the device is mounted includes an upper element 25, and legs 26, the molding 27 of the casing projecting outwardly with reference to the base, in the manner illustrated.

A trough 28 extends around the four sides of the device, and the curtains, or inner walls extend into the trough, and may be secured, if desired, by means of engaging devices 29. The trough is provided with an overflow device 30, and it is designed 80 that the water connected by the textile material shall pass into the trough, a small quantity collecting there, and any excess being discharged by the overflow device. The textile walls will be kept sufficiently moist 85 to permit of constant evaporation, the air passing through the outer wall of wire netting or the like. The water collecting in the trough 28 will serve to protect the food in the safe, from ants, or the like, and 90 the base including the trough may be used when desired for mounting a small refrigerator or ice box, the same protection from 95 insects being afforded.

The trough 28 is shown in Figure 5 as 100 being shaped like a rectangular frame including enlarged corner portions 32 which surround the legs 26, an inner upwardly projecting sleeve or the like 33 being of a size to fit the legs, and permitting of the 105 construction of a water-tight continuous trough of such character that there will be no exposed place where ants can pass from the legs to the upper structure when the trough contains water. The intervening 110

portions of the trough provide for the curtains which also extend into the corner portions.

Having thus described the invention, I 5 claim:

In a device of the class described, a casing including legs, a frame and outer perforated walls, inner walls of textile material, a water tank in the upper portion of 10 the casing, a trough surrounding the lower portion of the casing, the textile material extending into the upper tank and into the trough, said trough comprising a structure including a rectangular enlarged portion at 15 each corner, a sleeve projecting upwardly from the center of each rectangular portion

and adapted to surround the leg at that point, and narrow channels communicating with the rectangular portions, adapted to receive the lower edge of the textile material, and permitting of the flow of fluid entirely around each leg and the sleeve therefor, and from one of said enlarged rectangular portions to the remainder of said portions, the sleeves being approximately 20 square in cross section and being in alignment with the narrow channels at points of connection thereof with the rectangular enlarged portions.

In testimony whereof I affix my signature.

JOHN S. PIHLSTROM.
